ARM OR LEG EXERCISER

Bohdan Posatsky, P.O. Box 553, Santa Clara, Calif.
Filed July 17, 1962, Ser. No. 210,521
5 Claims. (Cl. 272—80)

This invention relates to mechanical exerciser devices and more particularly to an arm or leg exerciser.

It is an object of the present invention to provide an arm or leg exerciser that will be especially adaptable for physical therapy and will be efficient in operation whether in vertical or horizontal position.

Another object of the present invention is to provide an arm or leg exerciser that is adjustable for varying individual requirements.

A further object of the present invention is to provide an arm or leg exerciser that can be mounted on a frame and attached to a door by means of C-clamps.

Other objects of the invention are to provide an arm or leg exerciser bearing the above objects in mind which is of simple construction, has a minimum number of parts, is inexpensive to manufacture and efficient in operation.

For other objects and for a better understanding of the invention, reference may be had to the following detailed description taken in conjunction with the accompanying drawing, in which:

FIGURE 1 is a vertical view of the present invention shown in elevation and partly broken away;

FIGURE 2 is a fragmentary side view taken on the lines 2—2 of FIGURE 1;

FIGURE 3 is a top plan view of the frame;

FIGURE 4 is a view taken on the lines 4—4 of FIGURE 3; and

FIGURE 5 is a side view of FIGURE 3.

Referring now more in detail to the drawing, an exerciser 10 made in accordance with the present invention is shown to include a base plate 12 with a U-shaped bracket 14 fixedly secured centrally of the upper surface. An elongated eye rod 16 is freely received within bracket 14 and is pinned by pivot pin 18 which is received through eye rod 16 and bracket 14. A shoe 20 having an asbestos lining 22 secured to its bottom surface is in frictional engagement with the arcuately curved surfaces of bracket 14. A hollow and circular cup 24 abuts with the top of shoe 20 and freely receives a coil spring 26. The upper end of coil spring 26 is freely received by cup 28 of circular configuration. A knurled tension spring nut 30 is threadingly received by eye rod 16 above cup 28 thus providing adjustable tension upon spring 26. An internally threaded bushing 32 is threadingly received by eye rod 16 and provides for adjustment in height of exerciser 10 and a lock nut 34 secures it in position. An elongated tubular sleeve 36 is freely received at the upper end of eye rod 16 and a spherical knob 38 is fixedly secured to the upper end of sleeve 36. A sandal 40 is secured to sleeve 36 below knob 38 by a pair of circular clamps 41 which are adjustable so that sandal 40 may be slid up or down upon sleeve 36. Sandal 40 has a plurality of elongated and rectangular slots 42 which receive adjustable straps for holding the limb of an individual. A pair of parallel bars 46 having a plurality of openings 48 are secured to a pair of parallelly spaced apart cross bars 50 having a plurality of openings 52. Bars 46 with cross bars 50 provide frame means for clamping to a support structure such as a door or a chair. A pair of clamps 54 are secured one to each bar 46 and are adjustable by threaded screws 56. Clamps 54 are secured to bars 46 by fasteners 58.

As previously described, the frame means comprising the bars 46 and the cross-bars 52 is secured to a door, chair or any suitable support structure through the clamps 54. The base of the bracket 14 can be secured to the

2

frame by means of suitable fasteners passed through the holes 48.

In operation, the individual using the device places his leg or arm in the sandal 40 and straps it into place with the straps provided. When placing a foot into the sandal 40, the position of the foot will be to have the heel rest against the wide wall section and the toes project toward the narrow wall section. With an oscillating motion he carries sleeve 36 back and forth and the asbestos lining 22 provides friction against the arcuate curved vertical sides of bracket 14. When a chair is desired to be used, the fasteners are placed into the openings 48 and the exerciser is secured to the chair. When it is desired to suspend bars 46 and their cross bars 50 clamps 54 are placed over the edge of a door and the clamp screws 56 are rotated until clamp 54 is secured to the door.

It will be noted that the radius of bracket 14 may be taken from the pivot pin 18 or directly beneath depending upon the desirability of forward or backward motion to increase the tension.

While various changes may be made in the detail construction it shall be understood that such changes shall be within the spirit and scope of the present invention as defined by the appended claims.

What I claim as new and desire to protect by Letters Patent of the United States is:

1. A limb exerciser comprising a bracket with spaced confronting walls having conforming semi-cylindrical configurations along the periphery thereof, a rod having the proximal end thereof disposed between said walls, said rod being formed with an opening in the proximal end thereof, a shoe carried by said rod, friction lining attached to said shoe in confronting relation with the periphery of said walls, a pivot pin carried by said walls and received by said opening in said rod for supporting said rod for pivotal movement, said shoe being spaced from said pivot pin a predetermined distance whereby said friction lining is in continuous frictional engagement with the periphery of said walls, and a coil spring freely receiving said rod and arranged to transmit a force upon said shoe to urge said shoe toward said walls for maintaining said friction lining in frictional engagement with said walls.

2. A limb exerciser comprising a bracket with spaced confronting walls having conforming semi-cylindrical configurations along the periphery thereof, a rod having the proximal end thereof disposed between said walls, said rod being formed with an opening in the proximal end thereof, a shoe carried by said rod, friction lining attached to said shoe in confronting relation with the periphery of said walls, a pivot pin carried by said walls and received by said opening in said rod for supporting said rod for pivotal movement, said shoe being spaced from said pivot pin a predetermined distance whereby said friction lining is in continuous frictional engagement with the periphery of said walls, a coil spring freely receiving said rod and arranged to transmit from one end thereof a force upon said shoe to urge said shoe toward said walls for maintaining said friction lining in frictional engagement with said wall, and means adjustably positioned along said rod for abutting against another end of said spring to regulate the frictional engagement between said friction lining and said wall.

3. A limb exerciser comprising a bracket with spaced confronting walls having conforming semi-cylindrical configurations along the periphery thereof, a rod having the proximal end thereof disposed between said walls, said rod being formed with an opening in the proximal end thereof, a shoe carried by said rod, frictional lining attached to said shoe in confronting relation with the periphery of said walls, a pivot pin carried by said walls and received by said opening in said rod for supporting

said rod for pivotal movement, said shoe being spaced from said pivot pin a predetermined distance whereby said friction lining is in continuous engagement with the periphery of said walls, a coil spring freely receiving said rod and arranged to transmit from one end thereof a force upon said shoe to urge said shoe toward said wall for maintaining said friction lining in frictional engagement with said walls, means adjustably positioned along said rod for abutting against another end of said spring to regulate the frictional engagement between said friction lining and said wall, and a sandal carried by the free end of said rod and adapted to receive a limb of an operator.

4. A limb exerciser as claimed in claim 3 and including means for adjustably securing said sandal along the free end of said rod.

5. A limb exerciser comprising a frame adaptably secured to a support structure, a bracket detachably secured to said frame, said bracket being formed with spaced confronting walls having conforming semi-cylindrical configurations along the periphery thereof, a rod having the proximal end thereof disposed between said

5

10

15

20

walls, said rod being formed with an opening in the proximal end thereof, a shoe carried by said rod, friction lining attached to said shoe in confronting relation with the periphery of said wall, a pivot pin carried by said wall and received by said opening in said rod for supporting said rod for pivotal movement, said shoe being spaced from said pivot pin a predetermined distance whereby said friction lining is in continuous frictional engagement with the periphery of said walls, and a coil spring freely receiving said rod and arranged to transmit a force upon said shoe to urge said shoe toward said wall for maintaining said friction lining in frictional engagement with said walls.
